United States Patent Office

Des. 211,568
Patented July 2, 1968

211,568

STORE FRONT TOP

Eugene M. Ellner, Huntington, N.Y., assignor to Ellner & Pike Inc., Westbury, N.Y., a corporation of New York

Filed June 9, 1967, Ser. No. 7,468

Term of patent 14 years

(Cl. D13—1)

FIG. 1.

FIG. 2.

FIG. 3.

FIG. 1 is a front elevational view of the store front top of the present invention;

FIG. 2 is a side elevational view looking from the left of FIG. 1; and

FIG. 3 is a side elevational view looking from the right of FIG. 1.

I claim:

The ornamental design for a store front top, as shown.
